DESIGN FOR A SPOON OR OTHER ARTICLE OF FLATWARE

William S. Warren, Meriden, Conn., assignor to
Pillsbury Flour Mills Company, Minneapolis,
Minn., a corporation of Minnesota

Application August 2, 1940, Serial No. 94,137

Term of patent 14 years

To all whom it may concern:

Be it known that I, William S. Warren, a citizen of the United States and residing in the city of Meriden, New Haven County, State of Connecticut, have invented a new, original, and ornamental Design for a Spoon or Other Article of Flatware, of which the following is a specification, reference being had to the accompanying drawing, forming a part thereof, wherein,

Fig. 1 is a plan view of a spoon, on an enlarged scale, showing my new design;

Fig. 2 is a back or reverse plan view of the spoon on a scale substantially the same as that of the actual spoon.

Fig. 3 is a section taken on the line 3—3 of Fig. 1 as indicated by the arrows.

I claim:

The ornamental design for a spoon or other article of flatware, substantially as shown and described.

WILLIAM S. WARREN.
